UNITED STATES PATENT OFFICE

157,823

ICE-BOX DISH

Mary S. Wright, New York, N. Y.

Application March 25, 1948, Serial No. 145,337

Term of patent 14 years

(Cl. D44—10)

To all whom it may concern:

Be it known that I, Mary S. Wright, a citizen of the United States of America and a resident of New York, in the county and State of New York, have invented a new, original, and ornamental Design for Ice-Box Dish, of which the following is a specification, reference being had to the accompanying drawing forming part thereof, in which:

Fig. 1 is a top plan view of an ice-box dish embodying my design.

Fig. 2 is a side view thereof.

Fig. 3 is an end view.

Fig. 4 is a cross-sectional view on the line 4—4 of Fig. 1 showing the configuration of the ends of the dish.

I claim:

The ornamental design for an ice-box dish, as shown.

MARY S. WRIGHT.
